UNITED STATES PATENT OFFICE.

FRED R. ALLEN, OF PROVIDENCE, RHODE ISLAND, ASSIGNOR TO EUGENE F. BOWEN,
OF PROVIDENCE, RHODE ISLAND.

SURFACING-MACHINE.

992,730.

Specification of Letters Patent.

Patented May 16, 1911.

Application filed August 8, 1910. Serial No. 576,084.

To all whom it may concern:

Be it known that I, FRED R. ALLEN, a citizen of the United States, residing at the city of Providence, in the county of Providence and State of Rhode Island, have invented certain new and useful Improvements in Surfacing-Machines, of which the following is a specification, reference being had therein to the accompanying drawing.

10 This invention relates to floor surfacing machines and has for its object to provide a machine of this character that is very simple and inexpensive in construction, easy to manipulate, and effective in its operation.

15 A further object of the invention is to provide means whereby the surfacing rolls will be automatically raised from the floor immediately upon a cessation of the traverse motion of the carriage to prevent the rolls 20 from cutting into the floor, and to remain in this raised position until the machine is again moved forward, when the rolls will at once reengage the floor and continue their work as before.

25 Another object of the invention is to provide a machine of this character that may be readily converted from an abrading into a polishing machine so that a single machine may be adapted not only to rough out, but 30 to finish and also wax or polish the floor. By a slight adjustment in my improved machine the usual abrading rolls may be removed and the machine adapted to receive and operate a large flat faced disk, the same 35 having either an abrading or a polishing face as desired and adapted to work under radiators, steam pipes, and similar difficult places where the ordinary roll cannot reach.

Another feature of the invention is that 40 the head may be turned up on a slight angle so as to receive and operate a cone-shaped roll which is best adapted for some purposes, such as getting into corners, etc.

With these and other objects in view, the 45 invention consists of certain novel features of construction, as will be more fully described and particularly pointed out in the appended claims.

In the accompanying drawings: Figure 50 1— is a side elevation of the complete machine showing the resilient handle by which the machine is operated. Fig. 2— is an enlarged view, partly in section, illustrating the construction of the machine more in detail. Fig. 3— is a front elevation of the

machine showing the rolls and their bearings in section. Fig. 4— is a detail showing the manner of connecting the spring handle to the machine. Fig. 5— is a front elevation illustrating the supporting roller 60 and its bearing yoke which is vertically slidable in the adjustable sleeve, shown in section, also the springs on said yoke which raise the abrading rolls from the floor as soon as the operating pressure is relieved 65 from the same. Fig. 6— is a side elevation of the bearing sleeve showing the same turned at right angles, its abrading rolls removed and a disk in operative position in said bearing. Fig. 7— is a plan view showing the bearing sleeve and disk in operative position thereon. Fig. 8— is a small side elevation showing a section through the bearing and a portion of the bearing sleeve. Fig. 9— is a small detail showing the bearing head turned off at an angle for the purpose of receiving and operating a cone-shaped abrading roll.

Referring to the drawings, 1 designates a frame having a motor supporting platform 2 with downwardly extending sides 3—3 in which the main supporting wheels 4—4 are rotatably mounted on the shaft 5. Beneath this platform and midway between the wheels is a long tubular bearing member 6 which extends from the rear of the platform some distance forward and is for the purpose of receiving and providing a bearing for the driving shaft 7, which shaft receives its rotating motion from the electric motor 8 through the pulley 9, belt 10 and pulley 11 mounted on the rear end of said shaft. The forward end of this shaft is provided with a pinion 12 preferably of the spiral type. The outer end of the main 85 bearing member 6 is finished and reduced on its external surface at 13 forming a trunnion for receiving an adjustable bearing sleeve 14. The outer end of this sleeve is provided with a pair of forwardly extending off-set 90 bearings 15—15 which receive the horizontal shaft 16 for supporting abrading or surfacing rolls 17—17 of suitable construction, and on this roll shaft 16, see Fig. 3, is mounted the driving gear 18 which meshes 105 with the corresponding pinion 12. This bearing sleeve 14 is preferably split longitudinally on one side as at 19, see Fig. 6, and is provided with binding bolts 20 whereby the sleeve may be rotated on its trunnion 110

and set and bound in any desired position thereon.

In order to raise the abrasive rolls from contact with the floor as soon as the machine 5 stops moving, I have provided a supplementary supporting roller 21 mounted in bearings 22, which bearings are in turn connected with upright rods 23 to work vertically through the ears 24 on each side of the 10 sleeve 14. This supplementary support 21 is located intermediate the wheels 4 and the floor dressing or surfacing devices, and springs 25 of a given tension are mounted to act beneath the ears 24 so as to normally 15 carry the weight of the outer end of the carriage and to raise the dressing device from the floor. A pair of springs 26 of lesser power may be adjusted to counteract in a measure the effect of upward pressure of the 20 lower springs by means of the nuts 27 threaded onto the upper ends of said rods.

An essential feature to the successful operation of my improved construction is the operating handle 28 which is preferably 25 made of small gas pipe or tubing bent in a U-shape, the ends being secured by set-screws 29, or other convenient means, in suitable pockets 30—30 on either side of the frame 1, the loop portion then extending 30 rearwardly and upwardly forming a convenient handle to be grasped by the operator for manipulating the machine. A yieldable handle of this character exerts a flexible pressure on the abrading rolls and allows 35 the rolls to readily yield and follow any unevennesses in the floor.

When it is desired to use a flat disk instead of the rolls for either grinding or polishing said rolls and their supporting shaft 40 are readily removed from the bearings 15 and the disk inserted therein. In doing this the bearing sleeve 14 is loosened on its trunnion and turned at right angles, bringing said bearings 15 in a vertical position. 45 The supporting roller and its connecting rods are then removed from the bearing sleeve as they are not now needed and the disk 31, which is mounted on the shaft 32, is inserted in position through the driving 50 gear 18 and the machine may then run as before. This disk may be covered with either abrasive or polishing material as desired.

When it is desired to use a cone, as illustrated in Fig. 9, instead of either the rolls 55 or the disk, the bearings 15 may be turned at a slight angle and a cone-shaped roll 33 positioned on the driving shaft and run.

The operation of my improved device 60 may be more fully described as follows: The operator grasps the yieldable operating handle and in forcing the machine ahead he naturally presses the surfacing rolls 17 down in contact with the floor with a yieldable tension against the action of the bal-

ancing spring 25. As the machine moves forward in the operator's hands the flexibility of the handle permits the roll to follow any slight unevennesses in the floor causing the rolls to quickly surface a new floor 70 or clean and re-surface an old one.

It is found in practice in either the automatic or the usual hand driven machines where the roll is set to press on the floor with a given tension, that when the traverse motion of the machine is stopped even if for an instant, as is the case while reversing the direction of the carriage, a groove or low place is cut in the floor. This detrimental effect is entirely obviated by the use of the 75 little roll 21 which supports the forward end of the carriage on springs 25 and 26, whereby as soon as the operator ceases to push the machine forward the pressure is at once relieved on the abrading rolls and said springs 80 immediately raise said rolls from the floor effectually preventing the same from cutting only while the carriage is receiving a traverse motion over the floor.

Another feature of my improved construction is that the rolls are on the front of the machine, the driving gear is in the center of the roll shaft between the rolls, the rolls are on the ends of this shaft each projecting beyond its respective side of the machine whereby the machine is adapted to work up close to the mop board or side of the room which is found in practice to be of great advantage.

After the floor has been cleaned or brought 90 to the desired surface with the abrading rolls it is found in many instances desirable to use the same machine for finally polishing and finishing the floor, and as it is found in practice that the flat face of a rotary disk is the most effective for this purpose, 95 simple and effective means have been provided whereby such a disk may be readily inserted into this machine and operated in a practical way. Abrading material, such as sand paper, may also be attached to this disk, if desired, which is found most convenient for use in surfacing the floor under radiators, steam pipes and the like.

The device is extremely simple and inexpensive in construction and effective in its operation, and is particularly adapted for surfacing the floors of dwelling houses and offices, as it is very easily transported and manipulated, and can be readily adapted for completing a job including both the roughing out, finishing and polishing of the floors.

Having thus described my invention, what I claim as new and desire to secure by Letters Patent, is:

1. A surfacing machine comprising a carriage, one or more surfacing rolls operatively mounted on said carriage, and means for automatically raising said rolls from the floor when the carriage ceases its motion.

2. A surfacing machine comprising a carriage, one or more surfacing rolls operatively mounted on said carriage, and means for automatically raising said rolls from the floor when the carriage ceases its forward motion. 5
3. A surfacing machine comprising a manually operated carriage, main supporting wheels for said carriage, a surfacing roll operatively mounted on said carriage, and a spring-depressed supplementary support connected with the carriage intermediate the main supporting wheels and said surfacing roll to automatically raise said roll from the floor when the carriage ceases 10 to be pressed forward by the operator. 15
4. A surfacing machine comprising a two-wheeled truck, a surfacing roll operatively mounted across the forward end of the machine and a resilient operating handle through which the pressure on the roll is applied to the surface to be dressed. 20
5. A surfacing machine comprising a two-wheeled truck, a surfacing roll operatively mounted across the forward end of the machine, a resilient operating handle through which the pressure on the roll is applied to the surface to be dressed, and spring means 25 through which the working pressure of said roll may be regulated. 30
6. A surfacing machine comprising a two-wheeled truck having a resilient operating handle, an elongated forwardly extending shaft bearing, a pair of surfacing rolls operatively supported across the forward end of said bearing, and driving means located 35 between said pair through which the same are operated. 40
7. A surfacing machine comprising a carriage adapted to be moved over the floor to be dressed, a pair of surfacing rolls op- 45 eratively supported across the forward end of said carriage at right angles to its path of travel, and driving means located between said pair through which the same are operated, the outer end of each roll extending beyond its respective side of the carriage and beyond the roll supports. 50
8. A surfacing machine comprising a two-wheeled truck having a resilient operating handle, an elongated forwardly extending shaft bearing located below the carriage frame, a pair of surfacing rolls mounted in relatively fixed bearings across the forward end of said carriage, and driving means located between said pair through which the same are operated, the outer end of each roll extending beyond its respective side of the carriage and beyond the roll supports. 55
9. A surfacing machine comprising a carriage, a device operatively mounted on said carriage, a driving shaft for said device, and means whereby the angle of said shaft may be variably adjusted and set relatively to the surface to be dressed. 60
10. A surfacing machine comprising a carriage, an elongated forwardly extending shaft bearing located on said carriage, a sleeve mounted to be adjusted axially on said bearing, shaft bearings carried by said sleeve, and a dressing device having its shaft mounted in said latter bearings through which said devices are rotated, said shaft being adapted through said adjustable sleeve to be set at any desired angle to accommodate dressing devices of different characters. 70
